UNITED STATES PATENT OFFICE.

SEBASTIAN ZIANI DE FERRANTI, OF HAMPSTEAD, LONDON, ENGLAND.

GENERATOR AND SUPERHEATER.

No. 828,202.

Specification of Letters Patent.

Patented Aug. 7, 1906.

Application filed May 23, 1905. Serial No. 261,899.

To all whom it may concern:

Be it known that I, SEBASTIAN ZIANI DE FERRANTI, a subject of the King of Great Britain and Ireland, residing at 31 Lyndhurst road, Hampstead, London, N. W., England, have invented certain new and useful Improvements in Steam Generators and Superheaters, of which the following is a specification.

10 This invention relates to turbines—such, for example, as those described in my application Serial No. 179,407, of October 31, 1903—in which highly-superheated fluid is to be used, and has for object to provide means 15 for preventing the superheaters becoming overheated, more especially when the turbine is stopped.

The invention consists of a combined boiler and superheater, through which the heating 20 medium passes in parallel, the amount of heat passing through the superheater being adjustable in relation to that supplied to the boiler.

In the following description steam will be 25 taken as an example of a condensable elastic fluid.

Referring to the accompanying drawings, forming part of this specification, Figure 1 shows a sectional plan of one form of my invention, in which a back draft can be produced through the superheaters. Fig. 2 shows a similar view of a modification, in which the gases to the superheater first pass through a number of boiler-tubes, the flow of 35 gases through the superheaters being regulated by outlet-dampers, while Fig. 2^a shows a modification combining the features of the structures shown in Figs. 1 and 2; and Fig. 3 shows a view of another modification, in which the boiler and superheater elements 40 are separately fired, the relative flow being adjusted by inlet or fire dampers.

Where desirable, the same reference-letters are used to denote corresponding parts in the 45 different drawings.

I wish it to be understood that the drawings are of a diagrammatic nature and are not to be taken as working drawings.

In carrying my invention into effect according to one form, as shown in Fig. 1, I 50 have a common fire-grate *a*, and from this passages lead, the boiler-tubes *b* being contained in one passage and the superheater-tubes *c* in other passages, or there may be one 55 or more passages for the boiler-tubes and one for the superheater, or two or more passages

for each may be provided, according to convenience. The passage which contains the boiler-tubes has a free passage for the draft from the fire right through. The passages 60 which contain the superheater-tubes, on the contrary, are each fitted with one or more dampers *d* at the far end from the fire. There is also at this far end an adjustable opening *e* into the end of each passage from the external air. In starting up the fire I close the dampers *d*, leading from the ends of the superheated passages, and open the dampers or the like controlling the openings *e* from the external air into this far end of the chambers. 70 By this means currents of cool air pass into the superheated chambers through these openings *e*, traversing the tubes in these chambers in the opposite direction to that of the ordinary draft, and enough air can thus be allowed to flow back to the fire to keep the superheater-tubes cool, while the hot products of combustion from the fire go entirely through the boiler *b* and on through the economizer *f* to the chimney. 80

In normal working the dampers to the air from the ends of the superheating-chambers are completely closed and the dampers *d* from the superheating-chambers are opened. The hot gases then traverse the boiler-tubes 85 *b* and the superheater-tubes *c* in parallel and then join in a common chamber *h* before passing through the economizer *f*. This economizer-chamber may also contain a portion of the boiler; but this is a matter of convenience 90 as regards the relative area of the different parts which it is desired to obtain. The dampers *d* out of the superheater-chambers by being opened more or less will determine the relative amount of heat going through the 95 boiler in relation to that going through the superheaters. In another case I modify the above arrangement, in so much as I use several rows of boiler-tubes *i* (see Fig. 2) completely across the end of the fire before the 100 boiler and superheater-chambers are reached, thus protecting the ends of the superheater-tubes and saving in some cases the necessity of the damper-openings *e* to the external air and back draft for cooling the superheater-tubes *c* during the time that steam is not 105 passed through them for superheating. The products may then be passed on through an additional section of boiler and the economizer or through the economizer only. In some cases I may use a combination of the 110 arrangement shown in Figs. 1 and 2, as shown

in Fig. 2^a, which in view of the fact that the same reference-letters are used therein as in Figs. 1 and 2 will be clear without further description.

5 According to another method, as shown in Fig. 3, I may employ separate fires *k l* for the superheaters *c* and the boiler *b*, respectively. In this case each fire sends its products through its own passage, these products then uniting and passing through an additional section of the boiler and the economizer or through the economizer only. In this case the regulation is obtained by the amount of fire on each grate and by more or less opening 15 the dampers (indicated at *m*) feeding each fire, thus determining the amount of heat put into each element.

Having thus described my invention, what I claim as new, and desire to secure by Letters Patent, is—

20 1. The combination in a single structure of groups of boiler and superheater tubes arranged side by side with a partition-wall between said groups, a grate extending across the said groups and across the front end of said partition, said groups being arranged parallel with each other and a chamber at the rear extending across the ends of said groups and partition with a group of tubes therein, substantially as described.

25 2. The combination in a single structure of a furnace, groups of boiler and superheater tubes arranged side by side and parallel with each other, a partition between said groups, a grate extending across the said groups and across the front end of the partition and means for regulating the relative heating of the said groups of tubes, substantially as described.

30 3. The combination in a single structure of a furnace, two chambers or ducts arranged side by side with an inlet at the front and an outlet at the rear, a partition separating the two groups of tubes, said tubes extending

vertically in said ducts and a grate from 45 which the hot gases pass into the front ends of the said ducts, substantially as described.

4. In combination in a furnace, a group of boiler-tubes, a group of superheater-tubes arranged alongside the boiler-tubes, a partition between the said groups of tubes, a screen of water-tubes extending across the front of the groups of boiler and superheater tubes and a grate from which the hot gases pass through the said group of screen-tubes 50 and in parallel through the groups of boiler and superheater tubes, substantially as described.

5. The combination in a single structure of boiler and superheater elements; means for 55 passing hot gases through said elements together with means for causing a back draft of cool air through said superheater elements.

6. The combination in a single structure of boiler and superheater elements; means for 60 passing hot gases through said elements together with means including an opening to the external air and a damper for causing a back draft of cool air through said superheater elements.

7. In combination a group of boiler-tubes, a group of superheater-tubes arranged alongside the group of boiler-tubes and parallel therewith, a partition between the two groups of tubes forming ducts having each an inlet 70 at the front and an outlet at the rear for the hot gases, a screen of water-tubes reaching across the inlet end of both of said ducts, and a chamber to receive the hot gases from both of said ducts and a group of tubes in the said common chamber, substantially as described.

In witness whereof I have signed my name to this specification in the presence of two subscribing witnesses.

SEBASTIAN ZIANI DE TERRANTI.
